ION VALVE FOR PRODUCING ALTERNATING CURRENTS

Karl Erik Eriksson and Uno Lamm, Ludvika, Sweden, assignors to Allmänna Svenska Elektriska Aktiebolaget, Västerås, Sweden, a corporation of Sweden

Application July 7, 1933, Serial No. 679,343
In Sweden July 8, 1932

7 Claims. (Cl. 175—363)

In ion valves using metal vapor or inert gas under low pressure as conducting medium and serving to convert into alternating current either direct current or alternating current of another frequency, it has been already proposed to effect the transfer of the current from one anode to another by applying a voltage to the latter, either by impressing on the alternating current side a master voltage from a machine or the like, or by temporarily introducing a voltage between the first and the second anode at the instant of transfer. The present invention relates to another method of effecting the current transfer which in many cases gives a simpler arrangement, namely by means of an auxiliary anode (transition anode) which is temporarily subjected to a voltage varying in such way as to cause said anode to take over first the arc from the previously burning anode and then deliver it to the next main anode.

In the accompanying drawings, Fig. 1 shows diagrammatically one form of the invention and Fig. 2 a time diagram of its manner of operation. Figs. 3-7 show diagrammatically six other forms 25 of the invention.

Referring to Fig. 1, 1 designates a source of direct current, the negative pole of which is connected to the common cathode 13 of an ion valve while its positive pole is connected over an inductance coil 14 and the two halves of a transformer winding 15, 16 to the two main anodes 5, 6 of the ion valve. The secondary winding 17 of the transformer is connected to the alternating current network 2. The arrangement so far described is substantially known. According to the present invention, the positive pole of the direct current source is also connected to a transition anode 4 over a separate source of voltage 3 which is adapted to create an alternating voltage of substantially the type shown in Fig. 2. At the instant intended for extinguishing the anode 5, a positive voltage is thus impressed on the transition anode 4 so as to make its potential with respect to the cathode higher than that of the anode 5. The arc is then transferred from the anode 5 to the anode 4, and the impressed voltage should be sufficient for covering all voltage drops caused by the normal current in the circuit of said latter anode so as to maintain the normal current between said anode and the cathode. The transition anode 4 should also be so designed in respect of cooling etc. as to be able to carry the normal current during a short transitory period. As the anode 5 is normally blocked by an appropriate negative voltage

being applied to its control grid 25 from a battery 40, it cannot be reignited after once being extinguished. At an appropriate instant, substantially coinciding with that in which the additional voltage on the auxiliary anode 4 is changed from a positive to a negative value (Fig. 2), the normal blocking of the anode 6 is suspended by a positive voltage being impressed on its grid 26 from the battery 40 over a contact apparatus having rotating contacts 41, 42 and stationary contacts 43, 46. The auxiliary anode 4 will then have a lower total voltage than the anode 6, and the arc will be transferred to the latter. During the next semicycle the procedure will be the inverse of that described, so that the arc is transferred from the anode 6 over the anode 4 to the anode 5 as the blocking of the latter is suspended by a positive voltage being applied to its grid over the stationary contact 45. It is generally advisable to use a blocking grid 27 also for the anode 4 and to suspend the blocking thereof shortly before that of the anodes 5 and 6 by means of contacts 44, 44a on the contact apparatus.

In Fig. 3, the additional voltage on the transition anode 4 is obtained by means of a condenser 7 which is charged over a switch 8 from a source of direct current 9. An inductance coil 18 shown in dotted lines may facultatively be connected in series with said switch.

In Fig. 4, the switch 8 is replaced by a grid-controlled electric valve 12, and further a separate direct current source for charging the condenser has been made superfluous by introducing an inductance 10. When the condenser is discharged to the transition anode 4, the voltage on its lower conducting layer must sink below that of the upper one in order to cause the anode 6 to take over the current. If the valve 12 is released after the current through the anode 4 has been broken, a charging current therefore flows to the lower conducting layer of the condenser, and thanks to the inductance 10 this current will continue until the lower layer has been positively charged, that is, has obtained a higher potential than the positive pole of the direct current source. The action can be regulated by connecting an inductance 11 between the condenser and the transition anode.

If the condenser 7 is connected not directly but inductively to the transition anode 4 according to Fig. 5, the valve 12 for charging the condenser may form part of the main apparatus, that is, consist of a separate anode 12 therein having a separate grid control 22. The transformer for connecting the two circuits together

is designated by 19. The lower condenser layer should in this case be connected to the cathode of the main apparatus. Otherwise the manner of operation of this form is substantially analogous to that described in connection with Fig. 4.

The parts in Figs. 3-5 which have not been specially mentioned are analogous to those of Fig. 1 and designated in a corresponding manner.

The arrangements described may also be employed for the production of polyphase alternating currents, in which case one transition anode may be common to all phases or to certain phases. They may also be used for frequency conversion. Two examples of such arrangements are shown

15 in Figs. 6 and 7. In Fig. 6, the primary alternating current is supplied to the Y-connected primary winding of a transformer 31, the Y-connected secondary winding of which is connected with its neutral point to the cathode 13 of the ion valve and with the phase terminals to the midpoints of the two primary windings of the secondary transformer 32. The outer terminals of said last-mentioned windings are connected to the main anodes 35 and their midpoints over the transformer 19 of a condenser circuit 7, 10, 12, arranged in analogy with Fig. 5, to the transition anodes 34. Several such condenser circuits may be provided instead of a common one.

30 Fig. 7 differs from Fig. 6 substantially in that the secondary winding 32 has only one primary winding each half of which is connected to three windings 31 of the primary transformer, one for each phase, with corresponding anodes. In connection herewith, each phase has one winding for connection to the transition anode 34. The condenser circuit for producing the voltage on the latter is practically analogous to that of Fig. 6.

35 40 We claim as our invention:—

1. In ion valves for producing alternating currents, a cathode, a plurality of working anodes adapted to conduct alternatingly the current to said cathode, control grids for said anodes, means for impressing on said grids control voltages for blocking said anodes during certain intervals, and a transition anode combined with means for impressing a transitory voltage thereon sufficient to cause said transition anode to absorb the load current from one main anode and deliver same to the next anode.

45 50 55 2. In ion valves for producing alternating currents, a cathode, a plurality of working anodes adapted to conduct alternatingly the current to said cathode, control grids for said anodes, means for impressing on said grids control voltages for blocking said anodes during certain intervals, an auxiliary anode adapted to carry said current

during short time intervals, and means connected in series with said auxiliary anode for impressing a voltage sufficient to cover the voltage drop caused by said temporary current load.

3. In ion valves for producing alternating currents, a cathode, a plurality of working anodes adapted to conduct alternatingly the current to said cathode, control grids for said anodes, means for impressing on said grids control voltages for blocking said anodes during certain intervals, an auxiliary anode adapted to carry said current during short time intervals, and a condenser and a source of current connected between said auxiliary anode and the cathode.

4. In ion valves for producing alternating currents, a cathode, a plurality of working anodes adapted to conduct alternatingly the current to said cathode, control grids for said anodes, means for impressing on said grids control voltages for blocking said anodes during certain intervals, an auxiliary anode adapted to carry said current during short time intervals, and a source of current, an interrupting device, and a condenser connected between said auxiliary anode and the cathode.

5. In ion valves for producing alternating currents, a cathode, a plurality of working anodes adapted to conduct alternatingly the current to said cathode, control grids for said anodes, means for impressing on said grids control voltages for blocking said anodes during certain intervals, an auxiliary anode adapted to carry said current during short time intervals, and a source of current, a condenser and an electric valve connected between said auxiliary anode and the cathode.

30 35 40 45 50 55 6. In ion valves for producing alternating currents, a cathode, a plurality of working anodes adapted to conduct alternatingly the current to said cathode, control grids for said anodes, means for impressing on said grids control voltages for blocking said anodes during certain intervals, an auxiliary anode adapted to carry said current during short time intervals, and a source of current, a condenser, an inductance, and an electric valve connected between said auxiliary anode and the cathode.

7. In ion valves for producing alternating currents, a cathode, a plurality of working anodes adapted to conduct alternatingly the current to said cathode, control grids for said anodes, means for impressing on said grids control voltages for blocking said anodes during certain intervals, an auxiliary anode adapted to carry said current during short time intervals, and a source of current connected in parallel with a condenser between said auxiliary anode and the cathode.
